UNITED STATES PATENT OFFICE.

EUGÈNE HENRI MARIE EMILE DURAND, OF PARIS, FRANCE.

CIRCULAR-KNITTING MACHINE.

Application filed August 24, 1923, Serial No. 659,230, and in France August 31, 1922.

This invention relates to improvements in circular knitting machines, more particularly those which are provided with needles whereby the loops or stitches may be directly transferred from one needle onto another, and are intended for the manufacture of hose and half hose.

The improvements chiefly comprise the provision of reciprocating needles and guiding surfaces therefor; half of said needles performing rectilinear movements, and the other half performing identical movements in the upper part of the movement but moving rearwardly in the lower part of the movement; means being provided for passing by lateral inclination any one of the needles in the second-mentioned half behind its neighbor in the first-mentioned half. The machine also comprises sleys for producing the lateral inclination of the needles for the purpose of placing them exactly behind each other. The machine comprises, further, cam tracks with connection tracks or switches therein for operating the needles and sinkers (in normal working) during the transfer, and during the placing out of operation of the needles, during which the movements started are automatically continued.

Again, the machine comprises mechanism for starting at the desired moment the transfer movement and the placing out of operation of the needles and sinkers which are adapted to be withdrawn between constantly-acting lower sinkers; this mechanism ensuring that the length of thread taken up by a needle which has taken the place of the sinker which separated it from the next inoperative needle is constant and equal to that taken up by the neighboring needles.

In the said drawing,

Figure 1 is a vertical half-section on line 1—1 of Fig. 2, of the circular knitting machine.

Fig. 2 is a horizontal section on the line 2—2 of Fig. 1.

Fig. 3 is a detail view of the preceding figure.

Fig. 4 is a plan of Fig. 3, in which are shown only the sley and the needles.

Figs. 5 and 6 show the same detail as Figs. 3 and 4, but at the beginning of the transfer movement.

Figs. 7 and 7' show the needles in the various positions which they occupy during the operation of the machine.

Fig. 8 shows, diagrammatically, the cam tracks for the needles and the sinkers.

Fig. 9 is a diagram showing how the combination of the sinkers which are adapted to be withdrawn and the constantly acting sinkers attains its object.

Fig. 10 is a vertical section showing the chain and its attendant parts which operate the needles and sinkers when a reduction takes place.

Figs. 11 and 12 are side elevations of two details of said attendant parts.

Fig. 13 is a partial vertical section of the frame, in which are shown the respective positions of the needles and of the sinkers during the chief operations of ordinary knitting.

As will be seen (Figs. 1 and 2), the machine illustrated comprises a fixed frame carrying the cam tracks Y and Y' for controlling the needles X and X' controlling the sinkers, and a movable block l—l' rotating in the frame and carrying the needles a and b, the sinkers d and e and the sleys c.

The needles and their guide tracks (Fig. 13) are so made that the heads or hooks of the needles b move in a straight line 1b—2ab, while the heads of the others move along a broken line 1a—2ab. The needles a and b in their raised position will therefore move in the same way for drawing the thread, but one of them is displaced as they move downwards. The lower portions of the needles slide very loosely in the frame l', and their upper portions slide in the sleys c. The latter guide each needle a and b and, also, a sinker d. The sleys are made so that in their normal position, they keep the two needles a and b spaced apart and allow of the movements of the sinkers for ordinary working.

If, however, with the needles still in the low position, the sinker moves back to a greater extent as in Fig. 5, the sley c is forced to participate in this return movement, and the heads of the needles a and b in the said sley assume the positions shown in Fig. 6.

If the needles a and b (but b first) then rise, the hook of needle a engages with the recess of the needle b being slightly offset as described in my Patent No. 1,524,346, granted January 27, 1925. In addition to the sinkers d engaging with the sleys, the machine comprises between the said sleys, further sinkers e, which differ from the first sinkers only by the height of the portion

where the drawing and the transfer of the loop take place.

- The movements of the needles are controlled by means of jacks *f*, the butts of which enter the cam tracks. At the locus indicated by line O—1 (Fig. 8), which corresponds to the beginning of the knitting operation, the needles (Fig. 13) are at 2ab, and the sinkers at 2de; at O—5 a low point of the cam track produces a return movement of the sinkers shown at 3de (Fig. 13) in order to insure the drawing of the thread under, and not above, the hooks. At O—7, completion of the new loop, the needles and the sinkers are in the position shown in full lines, 1a and 1de (Fig. 13). In the next positions O—7" and O—7'', the needles are rising again, but to a less height than at O—1, up to 4ab of Fig. 13, for instance. At O—8, the needles have taken up exactly the same position as at O—1.

All the above movements of needles and sinkers are those used in ordinary working.

- Referring now to Figs. 7 and 7^a, the needle, on moving from positions 1 to 5, occupies successively the positions indicated; that is, the needle which holds the thread in its hook while the latch is folded down descends, but during this downward movement, the latch comes in contact with a stitch, and as the said stitch remains stationary in the general plane *m*—*n*, the latch of the needle is forced to close. The needle continues to move down and finally closes the stitch in the position 5. The needle continues its movement and, in passing from position 5 to position 7, it rises as in position 6 so as to open its latch, since the stitch which was held in the hook and which is compelled to remain in the general plane *m*—*n* forces the latch of the needle to open. The needle then descends with an open latch and takes up the same stitch; it then rises to position 8, after having cast off its stitch at the plane *m*—*n*. The needle then continues its rotation and after having passed through the remaining part of the cycle which it carries out normally, it returns to the position 1 where the operation recommences.

A decrease is effected as follows:

- In order to understand the movement, it must be observed that each sinker passes into the recess of the sley *c* and that the needles are coupled in pairs (the machine being provided with an even number of needles), the needles of each pair *a* *b* (Fig. 4) passing through the forked groove in the sley.

- When it is desired to decrease, the part or interponent *h* (Fig. 10) which corresponds to the needle on which the decrease is to be effected, is caused to contact with an obstacle or stop (as hereinafter indicated), so that it is pushed upwards to start the movement of the sinker *d*. The part *h* only starts

the pivoting of the sinker *d* about its axis *d'* and, during this pivoting, the butt of the sinker leaves the path or track *X* in which it was engaged, so as to come into the path *X'* for the decreases. Once the butt of the sinker which must assist in the decrease, has entered the groove *X'*, it does not leave it; that is, the sinker remains entirely apart and has no further action in the working of the machine.

Also, when a decrease is effected, the part 12 (Fig. 10) is actuated as hereinafter described to cause the butt of the needle to pass from the path *Y* to the path *Y'*, which needle, in order to effect a decrease, has given its stitch to the other needle of the pair.

The sinker *d* rotates outwardly and passing along to the end of the groove in the sley *c* (Fig. 4), causes the latter to slide outwardly. During this movement, the two needles *a* *b* slide in the forked grooves so that, at the end of the operation, they are in series (as indicated in Fig. 6). The movement of the needles at the rear of one another is concluded before they rise at position 7. The needles *a* and *b* rise together, but the needle *b* rises quicker than does the needle *a* (position 7', Fig. 7^a); this being due to the fact that the butts of the two needles are both still in the normal groove *Y* and that as the groove ascends and the needle *b* is in front of the needle *a* in the direction of the movement, it rises quicker than does the needle *a*. This upward movement, with the advance of the needle *b* on the needle *a*, is kept up at positions 7" and 7'', the movement apart of the needles being diagrammatically illustrated in Fig. 8.

At this moment, the needle *b*, placed in front of the needle *a*, has reached a level portion of the path *Y* and no longer rises, while the needle *a* continues to rise until it reaches the position 8, in which the two needles are at the same level. The part or rocker 12 (Fig. 10) then acts on the butt of the needle *b* (as hereinafter described), so that the butt passes from the path *Y* to the path *Y'* (Fig. 8); and while the needle *a* continues its circular movement of the machine, remaining always at the same level owing to the cross-section of the path *Y*, the needle *b*, owing to the cross section of the path *Y'*, it follows, withdraws (positions 9, 10 and 11) and, while withdrawing, the said needle *b* gives its stitch to the needle *a*. As a result, the number of needles of the machine has been reduced by a unit, and the needle belonging to the said unit has taken the stitch of the unit which has been withdrawn.

In order to understand the above described operation, it must be observed that the bracket 15 (Fig. 10), which carries the rocker 12 that acts on the butt of the needle

and the rod 14 that acts on the interponents h is actuated, at the required moment, by a plunger 10. The bracket 15 turns with the machine, but it may be placed, either manually or automatically, in the machine in front of the needle which effects the decrease; when the said needle is in the position where the decrease takes place.

In Fig. 8, the various radii O-1, O-2, 10 O-3, . . . O-11, correspond to the positions of the needles in Figs. 7, 7^a.

In the position O-1, the sinkers and the needles follow their normal cam tracks; that is to say, the butts of the sinkers are in the track X and the butts of the needles are in the track Y. The same applies to the positions O-2, O-3, O-4, O-5, O-6, the shape of the cam tracks X and Y imparting to the sinkers and to the needles 20 the movements required for forming the stitches.

From the position O-7, it will be seen that owing to the mechanism 10^a, herein-after described, being suitably actuated, one 25 of the sinkers advances towards the cam track X', while the associated sinker remains in the track X. The needles continue to pass through the track Y. In the position O-7', a sinker is seen, the butt of which is 30 in the track X, while the other moves through the track x and passes into the track X', both butts of the needles being in the track Y. The same applies to the positions O-7'', O-7''' and O-8. With regard to the position O-9, a butt of one of 35 the needles of the group considered moves towards the track Y' through the connection track r (owing to the position of the device 10^a) while the butts of the sinkers remain as before, one in the track X, and the other in the track X'.

With regard to the position O-11, it will be seen that for the group of sinkers and needles considered, the butt of one of the 45 sinkers is in the track X, the butt of the other sinker in the track X', the butt of one needle is in the track Y, while the butt of the other needle is in the track Y'. In these conditions, one needle and one sinker 50 have been disengaged, owing to their descending, one in the track X', the other in the track Y'.

The openings of the connection tracks are 55 closed by small doors held by light springs (not shown) to avoid accidental engagement of the needles and sinkers with the said tracks.

In order to cause at the desired moment 60 the engagement of a given sinker and needle with the connection tracks above referred to, the frame is provided with mechanism 10^a such as that shown in Fig. 10 and comprising a chain having a link per row of 65 loops contained in the article to be manufactured, and advancing to the extent of one

link per row made, as already utilized on other knitting machines. This chain is provided with projections on the links corresponding to the circular rows of loops during the manufacture or formation of which 70 rows it is desired to make for instance a reduction. A plunger 10 carried by a bracket 11 and provided at its end with a recessed cam track (Fig. 11) presses lightly against the chain and is pushed towards the interior 75 of the frame by the passage of a projection. The cam track in the plunger is adapted to engage with a projection 10b (Fig. 10) which will be hereinafter described, and as shown by Fig. 11, is first lowered and then brought 80 back to its initial height, and finally raised before coming out of the cam track, the interval between the two movements of lowering and raising corresponding to the angular distance on the cam tracks X and Y 85 of the connection cam tracks (Fig. 8).

A bracket 22 is provided which supports two toothed rings 16 and 18 engaging with a pinion 17 which is adapted to turn the two rings in opposite directions and to the same extent. The pinion is connected to a ratchet wheel 20 which is rotated by a pawl 24 (Fig. 12) raised by the passage of the boss 23 on the plunger 10. It will be understood that the pinion, ratchet wheel and the driving means for the same are such that each passage of the boss 23 turns the two rings 16 and 18 through an angle corresponding exactly to a certain number (two or four) of needles, and also that by adjusting the lowering of the pawl (for instance, by means of an eccentric 21) the movement of the rings to two or four needles may be regulated at will. Each ring carries one of the brackets 15 on which a rocker 12 is adapted to turn, the tail or projection 10b of which is adapted to engage with the cam track of plunger 10 when, as aforesaid, the latter is pushed towards the interior of the frame under the action of a projection on the chain. The first movement imparted by the cam—a lowering—swings the rocker and raises the rod 14 which, by means of the interponent h , turns the sinker about its axis and introduces the butt of it into the connection track x crossing over from the cam track X into the cam track X' (Fig. 8). It should be remembered that the cam tracks X X' controlling the sinkers (Fig. 8) and the cam track of plunger 10 (Fig. 10) are 110 both fixed, and that it is easy to make the device 10^a exercise an action on a sinker at the exact moment when the said sinker passes in front of the connection cam track.

In the same way, the second movement produced by the plunger cam track—a raising—presses the lip of the rocker 12 against the part 19 of the jack f connected to the needle a, and brings about the engagement 120 of its butt with the connection track r be- 130

tween the cam tracks Y and Y'. It must be pointed out that at the moment of the action of the device 10a, the needle is in its high position, and that the part 19 nearly touches the lip of the rocker 12 and also that the end projection of the needle is in front of the connection track, which is possible for reasons stated in the foregoing with reference to the sinkers.

- 10 The frame may comprise another device 10a similar to that described, but such that the needles and sinkers on which it acts would engage with the connection tracks M and N. The two devices may also have parts in common, such as for instance, the chain. In that way a circular frame is obtained working in the following manner:

Assuming it is desired to knit a tubular fabric decreased by two stitches every 10 rows, the successive decreases must always be effected by needles which do not belong to the same group of two needles, it being recalled that the needles in the machine form distinct groups of two needles. Let it be supposed that the tubular article being made comprises 40 stitches. The first two decreases will be made, for instance, so as to be diametrically opposite. The following decreases will be made so that one follows immediately after the first decrease, while the other immediately precedes the second decrease; the fifth and sixth decreases will be made so that the fifth decrease follows immediately the third decrease, and the sixth immediately precedes the fourth decrease, and so on. Thus two lines of decreases will be obtained which will start from the ends of a diameter of the knitted article so as to converge towards a junction point. It will be appreciated that this may be obtained by suitably arranging in the machine the devices 10a which cause the switching of the butts both of the sinkers and of the needles.

- 45 The operation is carried out as follows: By hand, or by operating on the pawl 24, the parts 15-12 are turned in order to bring them opposite two needles separated from each other by twenty needles, on which it is desired to produce the first two reductions, and the travel of the pawl 24 is set for two needles by means of the eccentric 21. The chain has projections on the tenth, twentieth, thirtieth, etc. links corresponding to the circular rows on which it is desired to make the reductions, and the machine is started. As long as a projection on the chain does not move in front of the plunger 10, the machine produces plain tubular work, but as soon as a projection moves in front of the plunger, it pushes the latter back and when the first rocker 12 arrives in front of the plunger cam track, the sinker d adjoining the needle b selected to make the first reduction engages with

the cross-track between X and X' and is rendered inoperative and carries with it in its return movement the sley c. At that moment, the needle under consideration and its neighbor a are low, and the sley has brought the head of needle a behind the needle b. They rise, b first, taking up successively the positions indicated in Figs. 5, 6 and 13 in such a manner that the loop which was carried by needle b has passed under the latch of that needle and surrounds needle a. At that moment, however, the jack f of the needle b is in its turn operated by the rocker 12 and passes into the connection track between the cam tracks Y and Y', carrying with it the needle in its descent and rendering it inoperative. In this movement, the needle leaves its loop on the next needle a.

After that, in front of the plunger 10 passes another rocker 12, and its action is identical with that of the first one. Finally, the pawl 24 meets the boss 23 provided on the plunger 10 and turns the ratchet wheel, the pinion and the rings so as to bring the rockers and two needles to their preceding position. The circular row is finished, the chain advances to the extent of one link, and the machine continues to produce plain tubular work until a new projection on the chain causes the operation of reduction.

After a reduction, a needle having been brought out of action, this group is reduced to a single needle. The saker also which was between the two needles has been brought out of action. Fig. 9 shows three groups of needles. The first group comprises the needles a', b', and the saker d' is between the two needles. The said group has at opposite ends the sinkers e' e''. The second group, which has been reduced, now comprises only a single needle a'', while the other needle b'' has descended, owing to the fact that its butt has entered the lower cam track. The said group no longer contains the saker d'', as the latter also has been brought out of action as its butt has entered the lower cam track Y'. It will therefore be seen that there is only a single needle a'' between the two sinkers e'', e'''. Finally, the third group is a normal group constituted by the needles a'', b'', similar to the first group constituted by the needles a', b'. This third group will remain in this position, the needles continuing to turn about the machine as long as the article being worked is not finished. When the work is finished and it is desired to reset all the needles, the saker d'' is again brought into its original position by reinserting its butt in the upper cam track X. The needle b'' also is restored to its working position by causing its butt to pass into the upper cam track Y. These operations may be carried out by hand.

It is understood that the above description

applies to the reduction in question, but it is possible that the manufacture of the product may necessitate several reductions, and in that event the description relating to the 5 starting of the new work for the group a^2 b^2 will apply to all the groups that have been reduced (that is, to all the groups for which the sinker and one of the needles have been brought out of action).

10 The object of Fig. 9 is chiefly to explain that when, after a reduction, the group of two needles is reduced to a single needle, the latter makes a stitch of the same size. It takes up the same length of wool or 15 thread. In fact, if the group a' , b' separated by the two sinkers e' , e^2 is considered, there is a length of thread which, passing from the top of the sinker e' , reaches the top of the sinker d' so as to return to the 20 top of the sinker e^2 . If the said length of thread is measured, it will be seen that it is exactly double the length of the thread of the second group which, it is known, is reduced to a single needle and makes only one 25 stitch, whereas the first group makes two stitches. In this case, the length of the thread is that which starts from the top of the sinker e^2 so as to return to the top of the sinker e^3 , and this length is exactly half the 30 length of the thread of the first group with two needles.

Obviously, the exact shape of the sinkers must be determined experimentally.

Having now particularly described and 35 ascertained the nature of my said invention and in what manner the same is to be performed, I declare that what I claim is:—

1. A circular knitting machine for shaped tubular articles, comprising a plurality of 40 needles; means for imparting reciprocatory movements thereto; means for guiding the needles during their movements; means for moving half of the needles rearwardly during the lower portion of their reciprocatory 45 movement to the exclusion of the other half; and means for inclining any one of the rearwardly-moved needles laterally so as to cause it to pass behind its neighbor in the excluded half.

50 2. A circular knitting machine for shaped tubular articles, comprising a plurality of needles; a rotary carrier therefor; a set of cam tracks wherein the needles are engaged for imparting reciprocatory movements to 55 them during their rotation with the carrier; sleys mounted on the carrier to rotate therewith and engaging the needles to pass certain of them behind their neighbors during the lower portion of their reciprocatory 60 movement; and means for operating the sleys.

65 3. A circular knitting machine for shaped tubular articles, comprising a plurality of needles; a rotary carrier therefor; a set of cam tracks wherein the needles are engaged

for imparting reciprocatory movements to them during their rotation with the carrier; sleys for passing certain of the needles behind their neighbors during the lower portion of their reciprocatory movement; sinkers 70 for operating the sleys; and a separate set of cam tracks wherein the sinkers are operatively engaged.

4. A circular knitting machine, according to claim 3, in which the cam tracks of each 75 set have connecting tracks between them to enable the needles and sinkers to pass from one track of the respective set to the other.

5. A circular knitting machine for shaped tubular articles, comprising a plurality of 80 needles; a rotary carrier therefor; means for imparting reciprocatory movements to the needles during their rotation with the carrier; sleys for passing certain of the needles behind their neighbors during the 85 lower portion of their reciprocatory movement; sinkers for operating the sleys; a set of cam tracks wherein the sinkers are operatively engaged having connecting tracks 90 between them to enable the sinkers to pass from one track of the set to the other; and an intermittently-acting mechanism for automatically effecting the movements of the sinkers through the connecting tracks.

6. A knitting machine, according to claim 95 5, in which the intermittently-acting mechanism embodies a plunger, a rocker operated thereby, connections between the rocker and a sinker for actuating the latter from the former, and a movable element provided with spaced projections for operatively engaging the plunger.

7. A knitting machine, according to claim 100 5, in which the intermittently-acting mechanism embodies a plunger, a rocker operated thereby, connections between the rocker and a sinker for actuating the latter from the former, and an endless chain having projections thereon at intervals for operatively engaging the plunger.

110 8. A knitting machine, according to claim 5, in which the intermittently-acting mechanism embodies a plunger provided with a cam track, a rocker having a portion engageable in said track, said rocker adapted to be operated consequent upon such engagement, connections between the rocker and a sinker for actuating the latter from the former, and a movable element provided with spaced projections for operatively engaging the 115 plunger.

9. A knitting machine, according to claim 5, in which the intermittently-acting mechanism embodies a plunger provided with a cam track, a rocker having a portion engageable in said track, said rocker adapted to be operated consequent upon such engagement, connections between the rocker and a sinker for actuating the latter from the former, and an endless chain having projections thereon 120 125 130

6 at intervals for operatively engaging the plunger.

10. A circular knitting machine for shaped tubular articles, comprising a plurality of 5 needles arranged in individual pairs; means for imparting reciprocatory movements to the needles; means for guiding the needles during their movements; means for moving one needle of each pair rearwardly during 10 the lower portion of its reciprocatory movement to the exclusion of the other needle; and means for inclining any one of the rearwardly-moved needles laterally so as to cause 15 it to pass behind the other needle of the respective pair.
11. A circular knitting machine for shaped tubular articles, comprising a plurality of needles arranged in individual pairs; means for imparting reciprocatory movements to 20 the needles; means for guiding the needles during their movements; means for moving one needle of each pair rearwardly during the lower portion of its reciprocatory movement to the exclusion of the other needle;
- and a plurality of sleys, one individual to 25 each pair of needles and engaging the same, to incline the rearwardly-moved needle of any pair laterally so as to cause it to pass behind the other needle of that pair.
12. A circular knitting machine for shaped 30 tubular articles, comprising a plurality of needles; a rotary carrier therefor: means for imparting reciprocatory movements to the needles during their rotation with the carrier; sleys mounted on the carrier to rotate 35 therewith and engaging the needles to pass certain of them behind their neighbors during the lower portion of their reciprocatory movement; and means for operating the sleys.
13. A circular knitting machine, according 40 to claim 12, in which the needles are arranged in individual pairs, and in which there is a sley individual to each pair and engaged with both needles thereof.

45 In testimony whereof I affix my signature.

EUGÈNE HENRI MARIE EMILE DURAND.
